United States Patent Office

Des. 215,733
Patented Oct. 28, 1969

215,733

CREDENZA OR SIMILAR ARTICLE

Frank D. Durando, New York, N.Y., assignor to Delmonico International Corporation, Maspeth, N.Y., a corporation of New York

Filed July 16, 1968, Ser. No. 12,789

Term of patent 7 years

Int. Cl. D6—01
U.S. Cl. D33—13

FIG. 1

FIG. 2

FIG. 3

FIG. 4

FIG. 1 is a front elevational view of a credenza or similar article embodying my new design;

FIG. 2 is a top plan view thereof;

FIG. 3 is a side elevational view thereof; and

FIG. 4 is a rear elevational view thereof.

The dominant features of my new design are shown in solid lines in the drawing.

I claim:

The ornamental design for a credenza or similar article, substantially as shown and described.
